PASTING MACHINE

Fred Cavallari and Peter Ori, Reading, Pa.

Application March 27, 1935, Serial No. 13,355

1 Claim. (Cl. 91—33)

The invention relates to a pasting machine and more especially to a roll wall paper pasting machine.

The primary object of the invention is the provision of a machine of this character, wherein paste or adhesive can be applied economically to the face of wall paper without waste of the paste or adhesive and in such a manner to enable the matching of the design appearing on several rolls 10 of wall paper thus eliminating any possibility of waste of the paper.

Another object of the invention is the provision of a machine of this character, wherein the construction thereof is novel in form so that excessive paste or adhesive applied to the paper will be combed therefrom during the pasting operation of the machine.

A further object of the invention is the provision of a machine of this character, which is simple in construction, thoroughly reliable and efficient in its operation, readily and easily handled, convenient for use, economical in the operation thereof, strong, durable, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claim hereunto appended.

In the accompanying drawings:

Figure 1 is a fragmentary top plan view of the machine constructed in accordance with the invention.

Figure 2 is a side elevation thereof.

Figure 3 is a vertical longitudinal sectional view through the machine.

Figure 4 is a fragmentary front elevation of the same.

Similar reference characters indicate corresponding parts throughout the several views in the drawings.

Referring to the drawings in detail, the stand 45 which is fragmentarily shown at A includes a horizontally disposed open frame 10 for removably receiving a paste or adhesive container in the form of a basin 11 open at its top and having a reinforced rounded marginal edge or rim 12 adapted to rest upon the top edge of the frame 10 for the support of the basin therein.

Midway of the frame 10 and at each side thereof is arranged a bearing 13 having a swinging releasing cap 14 fastened in working position for a spring clip 15 carried by the frame and these

bearings 13 have journaled therein the axle 16 of a paste applying roll or cylinder 17 which is freely rotatable and depends within the basin 11 for collecting paste or adhesive therefrom, the paste or adhesive being indicated at 18 within 5 the basin 11. The cap 14 of each bearing 13 permits the ready removal of the roll or cylinder 17 when the occasion requires.

Fixed to opposite sides of the frame 10 and disposed inclined in the direction of the roll or cylinder 17 are the opposed brackets 19 for the mounting or holding of a paper roll 20, the same being wall paper and is arbored by an irregularly faced journal 21 to prevent the slipping of the roll thereon when mounted in the machine and this 15 journal 21 has its ends engaged in and guided in slots 22 provided in the brackets 19 so that the roll 20 will gravitate and be urged toward the roll or cylinder 17 for contact therewith to have paste or adhesive applied thereto at one face of the 20 paper constituting such roll.

Arranged above the highest point of the roll or cylinder 17 is a paste comb 23 supported by uprights 24 fixed to and arranged at opposite sides of the frame and likewise arranged at opposite sides of the roll or cylinder 17. This comb 23 plays upon the side of the paper of the roll 20 receiving paste or adhesive from the roll or cylinder 17 so as to remove excess paste or adhesive and to eliminate paste at the extreme edges of 30 said paper. This comb includes the teeth 24' and the same being much finer at the ends of the comb than therebetween in order to comb off the 35 excess paste or adhesive while these teeth at the edges thereof are at an angle to further insure this process and thus prevent the edges of the paper from becoming soiled with paste or adhesive.

Swingingly connected with the frame 10 are upwardly arched or curved arms 25, the swinging 40 connection with said frame being had through pivotal bearings 26 and these arms have journaled therein a take-up or guide roller 27 which is located to be in close relation to the comb 23 when in working position. The arms 25 at the free 45 ends thereof carry a cross handle bar 28 while at the outside of the arms are keeper lugs 29 provided by the ends of a reinforcement rod 30 disposed crosswise of the arms and with each of these lugs 29 is engageable a hold-down hook 31 50 pivoted at 32 to the upright 24 and tensioned by a spring 33. In this manner the arms 25 will be latched down when the take-up or guide roller 27 is in working position with the paper of the roll 20 trained over the comb 23 and about the 55

said roller 27 as is indicated by dotted lines in Figures 2 and 3 of the drawings. These arms support a reflector 34 which enables a user of the machine to ascertain the design appearing on the 5 under face of the paper of the roll 20 delivered from the machine.

The reflector 34 has in association therewith a knife or blade 35 so that the paper may be severed at the point desired of the stretch thereof. It 10 will be obvious that as the paper is pulled from the roll 20 when threaded through the machine one face of the paper will receive paste or adhesive from the roll or cylinder 17 and the user of the machine can readily ascertain the design 15 on the other face of the paper through the use of the reflector 34 so as to match this design with other paper in applying the same to a wall. That is to say, the severed end of one stretch of paper carrying a determined design may be matched 20 with another stretch of paper for a continuity of the design on applying the paper to a wall.

The take-off of the paper from the machine is located in close proximity to the brackets for the roll 20 of paper so that the paste or adhesive applying area is at the minimum with respect to 25 the roll or cylinder 17 and the paper.

At the working end of the machine and carried by the frame 10 are work bed or table attaching brackets 36 so that a work bed or table top can be 30 conveniently associated with the frame 10 of the machine.

It is, of course, understood that by swinging the arms 25 upwardly and rearwardly the roller 27 will be carried away from the roll or cylinder 17 35 for freedom of access to the parts of the machine and such roller 27 when in working position is located close to the comb 23 and the arms will

swing forwardly and downwardly and latched or locked. This swinging of the arms permits the threading of the paper through the machine for the pasting operation thereof.

What is claimed is:

A machine of the character described comprising 5 a stand forming a support, a horizontally arranged removable paste container within said support, a paste applying roll detachably journaled with the support substantially centrally of 10 said container, arms fixed to the support and having channels in their inner sides inclined toward the paste applying roll, a journal having its ends loosely engaged in the channels for a roll of paper, upwardly arched arms above the paste applying 15 roll and each hinged at one end to the support for encircling a major portion of the upper part of said paste applying roll, a guide roll journaled in the last-named arms and located midway of the uppermost portion of the paste applying roll for reverse turning of paper from the 20 said roll of paper and maintaining said paper contacting with the paste applying roll, uprights on said support, a toothed comb carried by said uprights and operating on the paper at the side 25 contacting with the paste applying roll and having fine teeth at opposite ends and coarser teeth intermediate thereof for combing off excess paste, the teeth at the ends of the comb being angularly set and actuating to prevent the edges of the 30 paper from becoming soiled with paste, keepers on the last-named arms next to said uprights, and spring tensioned latches on the uprights and engaging the keepers to hold the said last-named 35 arms at rest next to the said comb.

PETER ORI.
FRED CAVALLARI.
